CLAIM

The ornamental design for a mass spectrometry instrument, as shown and described.

DESCRIPTION

FIG. 1 is a left side view of the mass spectrometry instrument.

FIG. 2 is a front view thereof.

FIG. 3 is a right side view thereof.

FIG. 4 is a back view thereof.

FIG. 5 is a top view thereof.

FIG. 6 is a bottom view thereof; and,

FIG. 7 is a right perspective view thereof.

Features shown in dashed lines form no part of the design as claimed.

In FIGS. 1-7, the dash dot lines form a boundary line across a surface feature to separate the surface feature into claimed portions and unclaimed portions of the design as claimed.
